UNITED STATES PATENT OFFICE.

JOSEPH LINDBURG, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed January 31, 1924. Serial No. 689,633.

To all whom it may concern:

Be it known that I, JOSEPH LINDBURG, a citizen of the United States, residing in Bay Ridge, Brooklyn, in the county of Kings, city and State of New York, have invented certain new and useful Improvements in Typewriting Machines, of which the following is a specification.

The present invention relates to a device for correctly determining the positions of types to be set into a typewriting machine, and for holding them in place while they are soldered to the type-bars.

A comparatively simple device for this purpose is herein disclosed which can expeditiously and conveniently be inserted into or removed from the typewriting machine, and when inserted locks the platen-frame in a fixed case-position. This device comprises a relatively stiff strip of spring-metal shaped to rigidly lock the main frame to the platen-frame of the machine. In this connection, a feature of the invention is to provide a case-shift-locking device of great utility by having means to increase the resiliency and better accommodate any variation found in the relative position between the main frame and the case-shift frame on different machines.

When a type-bar is swung to the anvil mount on the platen-shaft, it is held there against the action of the usual return spring until the solder has hardened, so as to avoid the risk of displacement of the block on the type-bar.

Another feature of this invention is to provide a simple improved means for holding the type-bars in position during the soldering operation in such a manner as to preclude all possibility of disturbance of the type on the bar after the type is adjusted, and for grasping the type-bar-holding means so that it can be more quickly and more easily inserted into and removed from the machine.

An object of the present invention is the provision of an improved adjustable mounting which will hold the type against displacement in its ascertained correct position while the same is being soldered to the type-bar, and the provision of means whereby this type-rest or anvil may be readily adjusted to such position that any type soldered to its bar while so in place on the anvil

must print in true alignment with the other type. This mounting may be affixed by a workman temporarily to the typewriting machine, and be adjusted and locked in correct position. Flexibility of adjustment angularly up and down, and backward and forward of the anvil are provided for in a plane at right angles to the platen-shaft. When any type selected for the purpose of setting the anvil is thrown by its bar against the anvil, the latter may be brought to position with its face or platform thereof flat against the face of the type, and with an aligning ledge on the anvil in engagement with the base of the type so selected.

Spring means to take up play between the screw and the anvil is also provided, and the threaded support for the adjusting screw may be slotted and provided with a tightening means to form a clamp which takes up the wear of the thread in the support for the screw, so that the screw does not turn too freely. The clamp-tightening means may also be used for locking the adjusting screw in a set position.

Another feature of the invention relates to the wedging device for clamping the main bracket and the anvil-supporting bracket or anvil-guide-support, so that the anvil is held after being adjusted angularly, backwardly or forwardly. The brackets may be fastened together or released, by simply tightening a thumb-screw. The improvement comprises fitting the leading end of the bolt that passes through the main bracket and the lugs on the anvil-guide-support with a wedging element having two prongs which have inclined edges and which straddle the bolt and engage the ends of a pin that passes through the end of the bolt to draw on the bolt by means of a thumb-screw threaded into the wedging element, consequently producing the desired clamping effect to rigidly hold the anvil in adjusted position. The bolt may be keyed to the main bracket to prevent its turning, so that the wedging element attached thereto is always in a convenient position for readily manipulating the thumb-screw.

Another feature of the invention provides an improved form of lugs on the anvil-guide-support to give maximum adjustable movement with relation to the length thereof by bifurcating the same and to permit

easy assembly and dismounting of the anvil-guide-support, at the same time providing simple means to prevent the anvil-guide-support from being accidentally removed from the main bracket. This latter comprises a screw threaded into the end of one of the lugs, the head of which is arranged to overlap the cut-out portion in the bifurcated lug and thereby form with the bolt extending through the bracket a stop to prevent the accidental removal.

A temporary or test platen may be provided, preferably mounted at one end of the same shaft that supports the type-block supporting device, so that the type that have been set in position may be tried out with other type as a check on the work before the device is dismounted from the type-writing machine.

Other features and advantages will hereinafter appear.

In the accompanying drawings,

Figure 1 is a view, in side elevation, partly in section, of a portion of an Underwood portable typewriter having the invention installed therein ready for the operation of setting and soldering a type-block.

Figure 2 is a sectional view, in side elevation, taken on the line 2-2 of Figure 4.

Figure 3 is a front elevation of the device, partly in section.

Figure 4 is a top view, partly in section, of the type-block-setting device shown in Figure 1.

Figure 5 is a perspective view of an improved form of device for holding the type-bars in position while soldering.

Figure 6 is a perspective view of a take-up spring shown in Figure 2.

Referring to the drawings in which the invention is shown applied to an Underwood portable typewriting machine, the main portion of the type-bar-setting device, designated as 10, see Figure 1, may be of proper proportion and design to enable a workman to temporarily substitute it for the usual platen. The device 10 may comprise a sleeve or hollow shaft 11, on one end of which may be suitably mounted a cylindrical test-platen 12, which preferably occupies less than half the length of the shaft 11. The outer end of the test-platen 12 may be provided with a ratchet-wheel 13 suitably positioned to be engaged by the usual detent platen-roll (not shown) on the machine for holding the test-platen 12 against rotary displacement. Each end of the hollow shaft 11 may have fitted therein a bushing 14, (only the one on the right being shown) of proper size to fit a usual platen-shaft 15. A set-screw 16 may preferably be provided at the right-hand end of the shaft 11 passing therethrough and through the bushing 14 to engage the platen-shaft 15, so that the

shaft 11 will turn therewith in the usual manner.

A type-positioning tool 17 is shown mounted at the right of the test-platen 12 on shaft 11, preferably near the center of its length. The positioning-tool 17 may comprise a main bracket 18 having a collar portion 19 fixed on the shaft 11, which provides for angular adjustment of the same and which is fixed on shaft 11 in a suitable manner, as by one or more set-screws 20. Upwardly from the collar-portion 19, a yoke-portion 21 extends which may be slotted to receive one or more, preferably two, rearwardly-extending bifurcated lugs 22 provided on an anvil-supporting bracket or anvil-guide-support 23 for adjustably mounting the latter to the main bracket 18. A pin 24 provided with a head 31 may pass through the middle of the yoke 21, and normally pass through the cut-out portion of the bifurcated lugs 22. The bifurcated lug form of connection offers an improved means for taking apart or assembling the positioning-tool 17. The lugs 22 are slidingly fitted into the slotted yoke 21, and by a novel clamping means, as wedging means 25, the lugs 22 of the anvil-guide-support 23 may be rigidly held in any adjusted position.

A wedging element 26 mounted on the leading end of the headed-pin 24 forms therewith the improved clamping means 25. The leading end of the headed-pin 24 may be flattened, and have a pin 27 passing through the flattened sides. The ends of pin 27 may be engaged by the inclined edges of two prongs 28 of the wedging element 26 which may straddle the leading ends of the pin 24. A thumb-screw 29 threaded through the upper portion of the wedging element 26 may bear on the pin 24 to draw the same into effective position, whereby the sides of the slotted yoke 21, which are slightly flexible, are pressed together between the head of the pin 24 and the wedging element 26, to rigidly clamp the lugs 22 of the anvil-guide-support 23 in position. A washer 30 may be interposed between the wedging element 26 and the side of the yoke 21.

The wedging element 26 may also be provided with a suitable means to hold the thumb-screw 29 in position, so that it can always be conveniently manipulated. This may be accomplished by driving the pin 24 through the left-hand ear of the yoke 21 with clearance holes through the other ears for the pin to keep the wedging element 26 in a relatively fixed position. The backward and forward, as well as the up and down, adjustment of the positioning-tool 17 may in part be effected by rotating collar-portion 19 of the main bracket 18 on the shaft 11, and further backward and forward adjustment of the anvil-supporting bracket 23 can be made by moving the bifurcated lugs 22 of

the anvil-supporting bracket 23 through the pin 24 in the desired direction after loosening the wedging element 26.

Novel means may be provided to prevent accidental removal of the anvil-guide-support 23 from its mounting, preferably by threading a screw 32 into any one of the legs of the bifurcated lugs 22, shown in Figures 2 and 4, as threaded into the right-hand upper one. In design the relation of the cross-section of the leg of lug 22 in which the screw 32 is threaded should be such that the screw 32 overhangs the cut-out portion of the bifurcated lug 22 and should not interfere with the sides of the slot in yoke 21. In so proportioning the parts, the maximum forward and backward adjustment of the anvil-supporting bracket 23 is allowed to take place, and the head of screw 32 will engage the body of the pin 24 to prevent the anvil-guide-support 23 from being accidentally removed from its mounting. By removing screw 32 the anvil-guide-support 23 may easily be assembled or dismounted from the main bracket 18.

Each usual type-bar 34 is soldered at its free end into the back of a type-block 33, and to remove the same it is only necessary to break the solder. Before affixing a new type 33 to the bar 34, it is necessary to properly position the same both lengthwise and angularly of the bar 34, and therefore the new type 33 must be rigidly held by the type-block-setting device 10 in the correctly determined position for the soldering operation.

Before beginning the type-bar-setting operation, it is preferable that a case-locking device 35 be inserted between the typewriter frame 36 and the case-shifting carriage 37 to prevent the shifting movement preliminary to and during the operation of setting and soldering the type, after which the usual platen may be replaced by the type-block-setting device 10. As shown in Figures 1 and 3, the case-locking device 35 consists of a relatively stiff spring folded on itself and shaped to be held in place against accidental displacement, and to lock the case-shifting frame 37 from movement relatively to the machine frame 36. The locking device 35 is also designed to be easily inserted into and removed from the machine.

To improve the utility of the case-locking device 35, an extra fold or loop 60 may be provided over the portion 61 which normally holds the case-shifting frame for more effectively accommodating variations of relative heights between the machine frame 36 and the case-shifting frame 37 in different machines, and the handle 62 may be enlarged to increase the resiliency of the device.

The typesetting tool 17 of the device 10 may next be positioned on shaft 11 at the printing point by loosening the set-screw 20,

sliding the collar portion 19 of the main bracket 18 along, and locking the same in any desired angular position thereon by retightening the screw 20; or the carriage of the machine may be moved to bring the tool 17 to the printing position by the usual letter-space mechanism, not shown.

The anvil-guide-support 23 through its rearwardly-extending lugs 22 is adjustably secured to the yoke 21 of main bracket 18 by the pin 24 and the wedging element 26, as explained above. The anvil-guide-support 23 may preferably be composed of a single block of metal and formed on its front side with means for slidably engaging with an anvil 38 for up-and-down movement, see Figure 4. An ear 39 may be offset rearwardly from the middle of the upper side of the anvil 38 and may be bifurcated to receive the lower portion of a grooved adjusting thumb-screw 40. By turning the thumb-screw 40, the anvil 38 may be adjusted up and down on the front side of the anvil-supporting bracket 23.

Since any appreciable play in the connection between the thumb-screw 40 and the ear 39 of the anvil 38 is liable to allow movement which will interfere with obtaining exact settings of the type-block 33, take-up means 65 may be provided to eliminate this undesirable effect. Take-up means 65 may preferably be in the form of a strip of flat spring bent over the top and down the sides of the ear 39 of anvil 38 and normally having the ends 66 thereof extend rearwardly into the grooved portions of the thumb-screw 40 between the under side of the ear 39 and the upper side of a shoulder of the groove on the thumb-screw 40, as shown in Figure 2.

To support the thumb-screw 40, the anvil-guide-support 23 may have a projecting piece 41 rearwardly extending from the top side thereof over the ear 39 of the anvil 38, which may have a downwardly threaded hole 42 to receive the screw 40. In order that the screw 40 may not move too freely in the threaded hole, when worn, a slit 43 may be made in the projecting piece 41 from the rear end thereof into the threaded hole 42, and a screw 44 extending transversely of the slit 43 may be provided to adjustably draw the split portions of the piece 41 together, thereby controlling the opening of the threaded hole 42. The screw 44 may be used as a clamping control, as described above, or as a means for locking the thumb-screw 40 against movement by tightening the same when the screw 40 has been set in an adjusted position.

In operation, the position and adjustments of the anvil 38 are first determined by aligning same with a type-block 33 and type-bar 34 other than the one which is to be set or soldered and which is known to be correctly

positioned for typing. After the bracket 18 and the anvil 38, above described, have been set at the printing point any type-bar 34 carrying a properly positioned type-block 33 may be swung to the anvil 38 by depressing on its type-key (not shown). The latter has a flat platform portion 45 for aligning the face of the type-block 33 thereon and an aligning ledge 46 at its lower edge to hold the base thereof. By means of the thumb-screw 29, the wedging element 26 may be loosened which releases the headed pin 24 to unclamp the lugs 22 from the yoke 21, and the anvil-supporting bracket 23 may be moved angularly, forwardly or backwardly as need be to make the face of the type-block 33 rest flat against the platform 45. Re-tightening of the wedging element 26 by turning the thumb-screw 29 fixes in place this adjustment. The thumb-screw 40 is then turned to move the anvil 38 until the ledge 46 thereof is in engagement with the base of the type-block 33. Thumb-screw 40 may be locked, if desired, by tightening the screw 44. The correct position of the anvil 38 will thus be determined. The type-block 33 used to ascertain such a position is released, and another type-bar 34 on which a type-block 33 is to be soldered is then thrown up to the anvil 38. A new type-block 33 is set with its face flat against the platform 45 of the anvil 38 and with its base aligned on the ledge 46. The type-bar 34 is then soldered or otherwise affixed in a well-known manner to the back of the type-block 33.

Before affixing each type-block 33, means easily inserted into and removed from the machine may be provided for holding the type-bar 34 forwardly against the usual mechanism (not shown), which normally returns the same to its rest position. This may preferably be in the form of a type-bar-holding device 47, such as is shown in operative position in Figure 1. The holding device 47 may consist of a flat spring punched and bent to have three extending portions 48, 49 and 50. The portions 48 and 50 may serve to hold the device in place, and 49, which has a finger or pressure edge 54, serves to hold the type-bar 34. The portions 48 and 50 are offset from one another, so that when the device 47 is compressed spaced ends 51 of portion 48 may be set to be substantially supported by a stationary part of the frame of the machine as under and against a bead 52 on the front frame of the typewriting machine. The portion 50 may be set under and against the usual type-bar segment 53. If the type-bar 34 has been swung forwardly previous to inserting of the device 47, then, when the latter is positioned as just described, the finger 54 offset laterally from the end of the portion 49 will bear with spring-pressure on the rear edge of the type-bar 34 holding the

same firmly in position with the type-block 33 flat against the anvil platform 45.

Two round holes 55 may be punched in portions 48 and 49 to offer convenient means for grasping the device 47 between the fingers to compress same when it is desired to insert it in or remove it from the machine. The type-blocks 33, when set, may be tested for alignment by moving the test-platen 12 to the printing point and typing in the usual manner. After setting the type-blocks 33 and testing the same, the device 10 may be replaced by the usual platen with assurance that the types are in correct aligned position for printing.

Variations may be resorted to within the scope of the invention, and portions of the improvements may be used without others.

Having thus described my invention, I claim:

1. A device for positioning type-blocks on pivoted type-bars of a revoluble-platen typewriting machine, comprising a main bracket, supporting means on which said bracket is adjustable in a plane at right angles to the platen axis, an anvil-guide-support adjustable angularly, forwardly, or rearwardly on said main bracket in a plane at right angles to the platen axis, an anvil mounted for up-and-down adjustment thereon, and means on the anvil-guide-support to guard against accidental removal from said main bracket and to facilitate assembling and dismounting thereof, said device being positionable at the printing point and adjustable to cause the face of a type-block to lie flat on the anvil and in correct printing alignment upon operation of a type-bar to carry the type-block against the anvil.

2. A device for positioning type-blocks on pivoted type-bars of a revoluble-platen typewriting machine, comprising a main bracket, supporting means on which said bracket is adjustable in a plane at right angles to the platen axis, an anvil-guide-support adjustable angularly, forwardly, or rearwardly on said main bracket in a plane at right angles to the platen axis, an anvil mounted for up-and-down adjustment thereon, and wedging means to clamp the anvil-guide-support to said main bracket in any adjusted position, said device being positionable at the printing point and adjustable to cause the face of a type-block to lie flat on the anvil and in correct printing alignment upon operation of a type-bar to carry the type-block against the anvil.

3. A device for positioning type-blocks on pivoted type-bars of a revoluble-platen typewriting machine, comprising a main bracket, supporting means on which said bracket is adjustable in a plane at right angles to the platen axis, an anvil-guide-support adjustable, angularly, forwardly, or rearwardly on said main bracket in a plane

- at right angles to the platen axis, an anvil mounted for up-and-down adjustment thereon, wedging means to clamp the anvil-guide-support to said main bracket in any adjusted position, and means to hold the wedging means in a convenient position for ready manipulation, said device being positionable at the printing point and adjustable to cause the face of a type-block to lie flat on the anvil and in correct printing alignment upon operation of a type-bar to carry the type-block against the anvil.
4. A device for positioning type-blocks on pivoted type-bars of a revoluble-platen typewriting machine, comprising a main bracket, supporting means on which said bracket is adjustable in a plane at right angles to the platen axis, an anvil-guide-support adjustable angularly, forwardly, or rearwardly on said main bracket in a plane at right angles to the platen axis, an anvil mounted thereon, adjustable connecting means to give up-and-down movement to the anvil, and take-up means to eliminate possible relative movement between said connecting means and the anvil, said device being positionable at the printing point and adjustable to cause the face of a type-block to lie flat on the anvil and in correct printing alignment upon operation of a type-bar to carry the type-block against the anvil.
5. A device for positioning type-blocks on pivoted type-bars of a revoluble-platen typewriting machine, comprising a main bracket, supporting means on which said bracket is adjustable in a plane at right angles to the platen axis, an anvil-guide-support adjustable angularly, forwardly, or rearwardly on said main bracket in a plane at right angles to the platen axis, an anvil mounted thereon, adjustable connecting means to give up-and-down movement to the anvil, and means to control the ease of movement of said connecting means and to lock, if desired, the connecting means in any adjusted position, said device being positionable at the printing point and adjustable to cause the face of a type-block to lie flat on the anvil and in correct printing alignment upon operation of a type-bar to carry the type-block against the anvil.
6. For a typewriting machine having pivoted type-bars, a type-soldering fixture insertable into the machine, having thereon a plurality of spaced means forming a substantial support to engage the frame of the machine, with means thereon to engage and hold against movement a type-bar which may have been swung to printing position, and an anvil for aligning the type to the printing position.
7. For a typewriting machine having pivoted type-bars, a type-soldering fixture insertable into the machine, having thereon a plurality of spaced means forming a substantial support to engage the frame of the machine, means thereon to engage and hold against movement a type-bar which may have been swung to printing position, with gripping means thereon to facilitate grasping the fixture for inserting the same into or removing it from the machine, and an anvil for aligning the type to the printing position.
8. For a typewriting machine, a type-soldering fixture insertable into the machine, having means thereon for locking the type-carrying means and the platen against relative displacement with respect to each other, with means thereon capable of accommodating variations of positions in different machines of the portions thereof to be locked by the fixture and to render the fixture more resilient, an anvil for aligning the type to a printing position, and means for locking the type against the anvil.
9. In a typewriting machine having a revoluble platen, type-carrying means comprising pivoted type-bars for carrying type-blocks to strike against the platen, a device to temporarily replace the platen for positioning the type-blocks to be affixed to the type-bars, comprising a main bracket having a pair of slots therein, supporting means on which said bracket is adjustable in a plane at right angles to the platen axis, an anvil-guide-support having a pair of bifurcated lugs extending into the slots in said bracket, a headed pin extending through the bracket and loosely through cutout portions of the bifurcated lugs to provide a connection between said bracket and anvil-guide-support for backward and forward movement, and angular adjustment of the anvil-guide-support on the bracket, displaceable means overhanging the cutout portions of the lugs to form with the body of the pin passing through said slots a stop to prevent accidental removal of the anvil-guide-support and to facilitate assembling and dismounting thereof, wedging means for clamping the anvil-guide-support in adjusted position, and an anvil adjustably supported on the anvil-guide-support for holding a type-block in correct printing alignment.
10. In a typewriting machine having a revoluble platen, type-carrying means comprising pivoted type-bars for carrying type-blocks to strike against the platen, a device to temporarily replace the platen for positioning the type-blocks to be affixed to the type-bars, comprising a main bracket having a pair of slots therein, supporting means on which said bracket is adjustable in a plane at right angles to the platen axis, an anvil-guide-support having a pair of bifurcated lugs extending into the slots in said bracket, a headed pin extending through the bracket and loosely through cutout portions

- of the bifurcated lugs to provide a connection between said bracket and anvil-guide-support for backward and forward movement, and angular adjustment of the anvil-guide-support on the bracket, displaceable means overhanging the cutout portions of the lugs to form with the body of the pin passing through said slots a stop to prevent accidental removal of the anvil-guide-support and to facilitate assembling and dismounting thereof, wedging means comprising a wedging element fastened to the leading end of the headed pin, tightening means to effect the wedging for clamping between the wedging element and the head of said pin the lugs in said slots of the bracket, and an anvil adjustably supported on the anvil-guide-support for holding a type-block in correct printing alignment.
11. In a typewriting machine having a revoluble platen, type-carrying means comprising pivoted type-bars for carrying type-blocks to strike against the platen, a device to temporarily replace the platen for positioning the type-blocks to be affixed to the type-bars, comprising a main bracket having a pair of slots therein, supporting means on which said bracket is adjustable in a plane at right angles to the platen axis, an anvil-guide-support having a pair of bifurcated lugs extending into the slots in said bracket, a headed pin extending through the bracket and loosely through cutout portions of the bifurcated lugs to provide a connection between said bracket and anvil-guide-support for backward and forward movement, and angular adjustment of the anvil-guide-support on the bracket, displaceable means overhanging the cutout portions of the lugs to form with the body of the pin passing through said slots a stop to prevent accidental removal of the anvil-guide-support and to facilitate assembling and dismounting thereof, wedging means comprising a wedging element fastened to the leading end of the headed pin, tightening means to effect the wedging for clamping between the wedging element and the head of said pin the lugs in said slots of the bracket, means to fasten the headed pin against relative movement with respect to the bracket for holding the wedging means in convenient position for ready manipulation, and an anvil adjustably supported on the anvil-guide-support for holding a type-block in correct printing alignment.
12. In a typewriting machine, type-carrying means comprising pivoted type-bars for carrying type-blocks to strike against the platen of the machine, a device to temporarily replace the platen for positioning type-blocks to be affixed to the type-bars in correct alignment, comprising a main bracket, supporting means on which said bracket is adjustable in a plane at right

angles to the platen axis, as anvil-guide-support adjustable angularly, forwardly, or rearwardly in said main bracket in a plane at right angles to the platen axis, an anvil mounted thereon, adjustable connecting means to give up-and-down movement to the anvil, and means on the anvil-guide-support for supporting the adjustable connecting means, having a clamping control thereon for regulating the ease of movement of said connecting means and, if desired, to lock the same in a set position.

13. In a typewriting machine having a revoluble platen, type-carrying means comprising pivoted type-bars for carrying type-blocks to strike against the platen, a device to temporarily replace the platen for positioning the type-blocks to be affixed to the type-bars, comprising a main bracket, supporting means on which said bracket is adjustable in a plane at right angles to the platen axis, an anvil-guide-support adjustable angularly, forwardly, or rearwardly in said main bracket at right angles to the platen axis, an anvil mounted thereon, and adjustable connecting means to give up-and-down movement to the anvil, having a resilient take-up at the connection to the anvil to eliminate possible relative movement therebetween.

14. For a typewriting machine having pivoted type-bars with detachable type-bearing blocks to be soldered thereto, a platen-shaft, a yoke-support on the platen-shaft, a type-aligning device adjustably supported by the yoke to predetermine the relative position of the type-block to the type-bar, and cam-actuated means to lock the aligning device in an adjusted position to the yoke-support during the operation of soldering a type-block to the type-bar.

15. For a typewriting machine having pivoted type-bars with detachable type-bearing blocks to be soldered thereto, a platen-shaft, a yoke-support on the platen-shaft, a type-aligning device adjustably supported by the yoke to predetermine the relative position of the type-block to the type-bar, and a screw-actuated wedging element to lock the aligning device in any adjusted position to the yoke-support during the operation of soldering a type-block to the type-bar.

16. For a typewriting machine having pivoted type-bars with detachable type-bearing blocks to be soldered thereto, a platen-shaft, a yoke-support on the platen-shaft, a type-aligning device adjustably supported by the yoke to predetermine the relative position of the type-block to the type-bar, and means to clamp the aligning device to the yoke-support in any adjusted position, including a clamping pin, a pair of wedges, and a wedge-operating thumb-screw.

JOSEPH LINDBURG.
